(57) **CLAIM**

The ornamental design for a front face of vehicle wheel, as shown and described.

DESCRIPTION

FIG. 1 is a perspective view of a front face of vehicle wheel, showing my new design; and,

FIG. 2 is a front elevational view of the invention.

The rear elevational view of the invention is not visible during normal use, and forms no part of the claimed design.

1 Claim, 2 Drawing Sheets

FIG. 1

FIG. 2
